FOOT TREADLE ELECTRICAL SWITCH

Roy Bloom, 13 Harcourt Road, Scarsdale, N.Y.

Filed Nov. 9, 1964, Ser. No. 82,514

Term of patent 14 years

(Cl. D26—13)

FIGURE 1 is a left side, top and front perspective view of a foot treadle electrical switch, showing my new design;

FIGURE 2 is a top plan view, to an enlarged scale;

FIGURE 3 is a right side elevational view, to an enlarged scale, the opposite side being substantially a mirror image thereof;

FIGURE 4 is a front elevational view, to an enlarged scale; and

FIGURE 5 is a rear elevational view thereof, to an enlarged scale.

I claim:

The ornamental design for a foot treadle electrical switch, as shown.
